(57) **CLAIM**

The ornamental design for a food slicing tool assembly, as shown and described.

DESCRIPTION

FIG. 1 is a perspective view of a food slicing tool in full assembly, showing my new design;

FIG. 2 is a front perspective of a single blade, representative of all blades within the assembly, showing an adjustable portion fully retracted, with the center post removed for ease of illustration;

FIG. 3 is a front perspective view thereof, showing an adjustable portion fully extended;

FIG. 4 is a left side view, wherein the right side view is a mirror image thereof;

FIG. 5 is a front view thereof;

FIG. 6 is a rear view thereof;

FIG. 7 is a top view thereof;

FIG. 8 is a bottom view thereof;

FIG. 9 is a front perspective view of the center post portion and a removable top portion, with the blades removed for ease of illustration;

FIG. 10 is a first side view thereof;

FIG. 11 is a second side view thereof, rotated 90° from the first side;

FIG. 12 is a third side view thereof, rotated 90° from the second side;

FIG. 13 is a fourth side view thereof, rotated 90° from the third side;

FIG. 14 is a top view thereof; and,

FIG. 15 is a bottom view thereof.

FIGS. 2-15 are isolated and close-up views representing individual components of the overall article as depicted in FIG. 1.
